(57) **CLAIM**

The ornamental design for a tablet computer, as shown and described.

DESCRIPTION

FIG. 1 is a front view of a tablet computer showing our new design in a first embodiment;

FIG. 2 is a back view thereof;

FIG. 3 is a partially enlarged view of a circled portion in FIG. 2;

FIG. 4 is another partially enlarged view of a circled portion in FIG. 2;

FIG. 5 is a top view of the tablet computer;

FIG. 6 is a bottom view thereof;

FIG. 7 is a right side view thereof;

FIG. 8 is a left side view thereof;

FIG. 9 is a partially enlarged view of a circled portion in FIG. 8;

FIG. 10 is another partially enlarged view of a circled portion in FIG. 8;

FIG. 11 is a front view of the tablet computer showing our new design in a second embodiment;

FIG. 12 is a back view thereof;

FIG. 13 is a partially enlarged view of a circled portion in FIG. 12;

(Continued)

FIG. 14 is another partially enlarged view of a circled portion in FIG. 12;
 FIG. 15 is a bottom view thereof;
 FIG. 16 is a top view thereof;
 FIG. 17 is a right side view thereof;
 FIG. 18 is a left side view thereof;
 FIG. 19 is a partially enlarged view of a circled portion in FIG. 18; and,
 FIG. 20 is another partially enlarged view of a circled portion in FIG. 18.

The broken lines shown in the drawings depict portions of the tablet computer that form no part of the claimed design. The broken lines encircling portions of the claimed design that are illustrated in the enlargements form no part of the claimed design.

1 Claim, 12 Drawing Sheets
